UNITED STATES PATENT OFFICE.

CHESTER P. WHITCOMB, OF SOMERVILLE, MASSACHUSETTS, AND JOHN G. GODFREY,
OF STEUBEN, MAINE; SAID WHITCOMB ASSIGNOR TO SAID GODFREY.

METAL WEATHER-STRIP.

1,104,334.

Specification of Letters Patent. Patented July 21, 1914.

Application filed May 8, 1913. Serial No. 766,315.

To all whom it may concern:

Be it known that we, CHESTER P. WHITCOMB and JOHN G. GODFREY, both citizens of the United States of America, and residents, respectively, of Somerville, in the county of Middlesex and State of Massachusetts, and of Steuben, in the county of Washington and State of Maine, have invented certain new and useful Improvements 5 in Metal Weather-Strips, of which the following is a specification.

This invention relates to a weather strip adapted to be interposed between the vertical edge of a sliding window sash and the 15 part of casing opposed to the said edge to form a tight joint between the sash and casing.

The invention has for its object to provide a one piece weather strip of suitable construction adapted to be securely attached to the casing and permit the sash to slide freely in contact with it.

The invention consists in the improvements which we will now proceed to describe 25 and claim.

Of the accompanying drawings: Figure 1 represents a perspective view of a weather strip embodying our invention. Fig. 2 represents a horizontal section showing a portion 30 of a window casing provided with our improved weather strip and one of the vertical members of a sash engaged with the strip. Fig. 3 represents a transverse section of the strip.

35 The same reference characters indicate the same parts in all the figures.

In carrying out our invention as shown by Figs. 1, 2 and 3, we form from a single strip of suitable sheet metal such as spring 40 bronze, zinc, or aluminum, a weather strip comprising a flat base which is composed of two parts 12 and 13, adapted to bear on the flat surface of a window casing 14, said parts being separated from each other by a 45 sealing rib 15 formed integral therewith and adapted to enter a deep groove 16 in one edge of a sash 17. A portion of the strip is bent backwardly from one edge of the base to form a resilient tongue 18 adapted to

spring outwardly from the outer side of the 50 base, the free edge of the tongue 18 being provided with a bead or projection 18^a adapted to bear yieldingly on the edge of the sash 17, which is provided with a shallow groove 19 adapted to receive the said projection. The opposite edge portion of the 55 base is bent inwardly to form a flange 20, said flange being adapted to enter the groove 21 which receives the usual parting bead 22, the flange 20 lying in the groove beside the 60 parting bead as shown by Fig. 2. The edge portions of the base are perforated to receive attaching nails or tacks 23, the portion 12 being provided with orifices 24 and the portion 13 and tongue 18 being provided with 65 coinciding orifices 25 and 26 to receive the attaching devices.

Each of the described embodiments of the invention is characterized by a wide flat base adapted to be secured at both of its edge 70 portions to the casing, and a spring tongue bent backwardly from one edge of the base and secured at its inner portion with the base to the casing, said tongue being provided with a projection adapted to engage 75 a groove in the edge of the sash and prevent the sash from rattling and exclude air from the outside.

We claim:

A one piece sheet metal weather strip 80 comprising a flat base, a sealing rib integral with the base and adapted to enter a groove in the edge of the sash, and a resilient tongue bent backwardly from one edge of the base, adapted to spring outwardly from the outer 85 side of the base, and provided at its free edge with a projection adapted to enter another groove in the sash, the inner portion of the tongue and the corresponding edge portion of the base being provided with co- 90 inciding orifices to receive attaching devices.

In testimony whereof we have affixed our signatures, in presence of two witnesses.

CHESTER P. WHITCOMB.
JOHN G. GODFREY.
